UNITED STATES PATENT OFFICE

HUGO PETERSEN, OF BERLIN-STEGLITZ, GERMANY

MANUFACTURE OF SULPHURIC ACID

Application filed February 24, 1927, Serial No. 170,663, and in Germany March 20, 1926.

This invention has reference to improvements in the manufacture of sulphuric acid by means of the oxidizing action of nitrogen oxids, and it refers more particularly to the 5 methods of producing high-grade sulphuric acid without the use of lead-chambers and by the use of nitrosulphonic or nitrosyl-sulphuric acid or of so-called nitrous vitriol as the main oxidizing agent, and among other 10 important objects, it is intended to increase the intensity and efficiency of the several working units and to accordingly limit the number and extension thereof. In view thereof the oxidation of the gases of sulphur-dioxid or of sulphurous acid is considerably 15 accelerated by providing for an undecomposed excess of free nitrosulphonic acid, for which purpose the strength of the nitrosulphonic acid employed in the several units or 20 enclosures is correspondingly regulated or, in the case of rinsing them with comparatively weak nitrosulphonic acid or nitrous vitriol, such increased amounts thereof are employed that in the parts of the plant em- 25 ployed for the production of the sulphuric acid itself a very high oxidizing efficiency is obtained with but a very limited amount of liberation of nitrogen oxids, so that the rinsing nitrosulphonic acid or nitrous vitriol 30 leaving said enclosures, will still be very high in available nitric oxids. Now I have ascertained in the further course of my investigations that this object will be most readily accom- 35 plished with a great reduction in the quantity of the nitrosulphonic rinsing acid, if enclosures of certain height and cross section are employed, and preferably with the simultaneous employment of a particularly suitable kind of packing or filling material. 40 By operating in this manner it has become possible to so regulate the manner of operation of the plant that the ratio of the nitrogen oxids liberated in the production enclosures from the nitro-sulphonic acid, expressed in 45 terms of nitric acid of 36 degrees Bé., to the amount of sulphuric acid produced, and expressed in terms of 60° Bé. sulphuric acid will be so much reduced that one part of liberated 36° Bé. nitric acid will correspond up 50 to 20 and more parts of sulphuric acid of 60° Bé. But there will already be a great ad- 55 vantage if this proportion would only be 3:1. As regards the reaction enclosures they may preferably comprise towers or tower-like pieces of apparatus. 60 In order to arrive at the oxidizing capacity of the nitrosulphonic acid above referred to it is of importance to impart certain dimensions to the reaction enclosures of the plant. The cross sectional area of the several units 65 should be regulated in accordance with the packing material employed for the enclosures, and should be so arranged and selected that the resistance produced for each ascending or vertical meter of the unit should not be less than $\frac{1}{4}$ millimeter (one fourth millimeter) water column. The maximum limit of the resistance employed should preferably be so arranged that it does not amount to more than six (6 millimeters) millimeters 70 water column for each vertical or ascending meter, inasmuch as otherwise the resulting friction would necessitate too much power for the movement of the gases, which would interfere with the judicious and economical 75 working of the process. The height of the enclosures will be governed by the cross sectional area employed, and such height may amount to 18 meters (59 feet) and even more. One single production enclosure will be suffi- 80 cient for the purpose of completely or substantially converting the gases of sulphurous acid into sulphuric acid. The remaining residues of the SO_2 -gases with this method of working will be so small that the enclosure 85 succeeding the enclosure for the production of acid will already operate as a Gay-Lussac, that is to say, the acid running off from such enclosures will be richer in nitrosulphonic acid than the acid fed to the several enclosures. Moreover, the acid running off from the enclosure where the production takes place should be so strong in nitrosulphonic acid that at least 25 percent of the amount of nitrosulphonic acid fed to said enclosure re- 90 main in the acid running off therefrom. This proportion of nitrous vitriol or of nitrosulphonic acid may however, amount to nine tenths ($\frac{9}{10}$) of the original charge, or, in the 95 case of a particularly well operating denitrat- 100

ing tower being placed before the production- enclosure, it may remain unchanged, that is to say, it would correspond to the original strength of nitrosulphonic acid.

5 A plant, arranged in accordance with the principles, above outlined would be constituted by one denitrating tower, only one tower for the production of sulphuric acid, and a plurality of Gay-Lussac-towers. A 10 decrease in the contents of nitrosulphonic acid will only occur in the denitrating tower in which the complete denitration of the amount of daily output required for commercial acid for the market is effected and 15 in the tower in which the production of acid takes place, while in all other towers of the plant there will be an increase of the contents of nitro-sulphonic acid. The denitrating tower may preferably be of such size, and 20 may be so arranged and constructed that it is of sufficient capacity to not only denitrate the daily output of commercial acid, but also additional quantities of nitrous vitriol or nitro-sulphonic acid. The "production"- 25 tower on the other hand, will be worked the more favorably, the higher is the amount of the acid denitrated in the denitrating tower, and the less will be the amount of oxides of nitrogen which are to be liberated in the 30 "production"-tower, and the acid will therefore run off from such tower with a correspondingly higher content of nitrosulphonic acid. There is however, a maximum limit for the amount of nitrous vitriol or nitrosulphonic acid to be denitrated in the denitrating tower, this limit being attained when the quantity of oxides of nitrogen evolved, expressed in terms of nitric acid of 36° Bé, amounts to one third of the sulphuric acid it 35 is desired to produce, and expressed in terms of sulphuric acid of 60° Bé.

As to the Gay-Lussac-enclosure only one tower or a tower-like apparatus will be found sufficient in many cases, and for ordinary purposes two such towers or enclosures 40 will have to be employed generally.

In the case above referred to, where there is the possibility of denitrating larger quantities of nitrosulphonic acid or of nitrous vitriol in the denitrating enclosure, the rinsing system is preferably so arranged that the acid, after the withdrawal of the commercial "production" acid, is delivered to the last 45 Gay-Lussac-tower from which it passes to the tower for the production of sulphuric acid, and thence it is delivered to the denitrating tower. In the case, however, of the Gay-Lussac apparatus and the "production"- 50 tower requiring a larger amount of rinsing acid than could be obtained from the denitrating tower after the withdrawal of the commercial "production"-acid, the rinsing 55 may be effected in one of the following two ways. I may either proceed by providing an 60 inside circulation for each of the absorption

towers or Gay-Lussac towers and for the "production"-tower for the production of sulphuric acid in addition to the rinsing acid coming from the denitrating tower which latter passes from one tower to the other, so 70 as to obtain the required amount of rinsing liquor for all of these enclosures; or in another modification, I may proceed by employing a portion of the acid of the "production"-tower together with the excess acid 75 running off from the denitrating tower as the circulating liquid for the entire plant.

By providing a gas pressure of $\frac{1}{4}$ to 6 (a quarter to six) millimeters water column for each vertical or ascending meter of the tower as above outlined, it becomes possible to make such towers, or tower-like enclosures or boxes or tanks of considerably larger cross sectional area than heretofore possible, and in consequence thereof plants may be constructed comprising considerably larger units of production than have been employed heretofore for tower-systems or even for chamber-systems. In accordance therewith it has become possible to erect plants embodying the 80 principles of my invention and comprising towers with diameters of 7, 10 and 14 meters (23 $\frac{1}{4}$, 32 $\frac{3}{4}$ and 46 feet respectively) which would correspond to a cross sectional area 85 without the brick lining of 39, 78 $\frac{1}{2}$ and 150 square meters. Nor are these dimensions to be regarded as the maximum limits.

The calculation of the cross sectional area of the towers required for a certain size of packing material of small size or for any other packing means is governed by the amount of gas to be passed through the system of apparatus. The measure of cross sectional area and the free spaces in the packing material should be adjusted and selected 90 to correspond to the volume of the gases, and in such a manner that the resistance above referred to of a quarter to 6 millimeters water column pressure may be obtained.

The available height, that is to say the 100 height of the tower section provided with filling material, should be made to correspond to the total packing space and to the cross section of the towers. Thus for instance, in the case of a quantity of gas of 110 5-hundred-thousand cubic meters in 24 hours and at an average temperature of about 50 degrees centigrade an available packing section of 4-thousand cubic meters would be required. Now, with a tower of 14 meters diameter equal to about 150 square meters cross section under the conditions mentioned the total height required for the available filling or packing space would amount to 27 meters. This total height of about 27 meters 115 would have to be distributed over three or four, or even over but two towers.

Broadly speaking, in accordance with the principles of my invention height and cross sectional measure of the units of apparatus 120

should be in inverse ratio, the height being reduced proportionate to an increase in the cross section of the apparatus. By resorting to a great cross sectional area the structural height of the units of apparatus may be reduced, which is a fact of great importance both from the point of view of costs of erection and of the general management of the plant.

10 The sum of the available heights of the several towers or enclosures serving for the production of the sulphuric acid proper and for the absorption of the nitrogen-oxides may be reduced to about 8 meters, as has been ascertained in practical working, or this total height may be increased up to 50 meters and more, as has been proved to be of advantage in other cases of practical operation. An increase in height affords the 20 advantage of a prolonged gas passage with an increased gas-velocity. By this means the gas is caused to be brought in contact and to react with the downwardly trickling liquid, so as to result in a quicker termination of 25 the reaction.

From practical considerations it will be advantageous to provide for equal cross sectional areas of the "production"-enclosure and of the absorption enclosures, and also 30 to provide similar kinds of packing or filling material and size of packing for both kinds of enclosures. But it is also admissible within the scope of my invention to make the "production"-enclosure for the manufacture 35 of the sulphuric acid of smaller cross sectional measure than the absorption enclosures with the same kind of filling or packing material, or in another modification the "production"-enclosure may have the same 40 cross section as the absorption enclosures, but a finer kind or distribution of packing material. This would result in an increased velocity of the gases and an increased friction in the reaction space.

45 The strength of the acids to be employed may be kept between 55 and 62 degrees Bé.; but a strength of from 58 to 60° Bé. has been found preferable. The water required in the course of the said sulphuric-acid process is preferably added in the production tower in the acid-production stage in thin jets and, in view of the strength of the acid in the different parts of said tower without substantial liberation of nitrous gases.

55 Other portions of water may be added in the denitrating tower, and thereby enter the system in the gases escaping from said denitrating tower or the like.

The rinsing system may preferably be arranged in such a manner that the acid leaving the "production"-tower less the amount to be withdrawn as the commercial product is caused to pass onto the last tower or an equivalent enclosure, and thence to the second before the last and so on as far as to

the "production" tower. In case there is but one absorption enclosure besides the "production"-enclosure the acid will only be circulated between these two enclosures. If the denitrating tower is adapted to denitrate more acid than would correspond to the quantity to be withdrawn as commercial product, the excess portion is passed to the last tower or enclosure. In case of a combination of only one absorption tower with the "production" tower the admission of the gases from the "production" tower into the absorption enclosure is preferably effected in the upper part of the same, so that the gases will give off their heat to the cooled acid fed to the enclosure, which will facilitate the absorption of the nitric oxids. In the case of employing impure gases one or several washing towers may be arranged before the denitrating tower or between the denitrating tower and the "production" enclosure.

A particularly favorable result is produced by providing for a subdivision of the gas current into a plurality of small gas jets as the result of packing or filling bodies or granules of about 3 centimeters (1.1 inch) size or less. By means of this kind of granulated or similar packing the gas current is split up into a great multitude of thin jets which are compelled to be forced and to emerge between the granules, so that said jets are brought into intimate contact with the rinsing liquid which is finely distributed as a thin coating on the surface of the said granules.

Upon the accompanying drawing I have illustrated diagrammatically and by way of exemplification the arrangement of the different units of a plant for the manufacture of sulphuric acid in accordance with the principles of my invention in vertical elevational view in Figures 1 to 5 of the drawing, showing various modifications to which the invention is adapted without, however, restricting the invention to these particular embodiments of the principles above outlined which in this exemplification are applied to towers which may be provided with different kinds of packing, such as ordinary regular filling or packing bodies as well as with granular packing of quartz or other suitable material of which latter particularly the smaller size-granules (1/2 to 1 inch diameter or less) are known to produce up to four times as much active surface as ordinary packing. The way of the rinsing liquid of nitrous vitriol or nitrosyl-sulphuric acid is indicated in the drawings and in Figures 1 and 2 I have also indicated the percentages of nitrous vitriol in the various stages of operation of the plant. In Figure 1 the method of operation with but one "production" tower is illustrated, the acid running off from this tower after the withdrawal of the quantity intended for commercial acid being fed to the last Gay-Lussac and

running off from the "production"-tower with at least 25% of its original strength. Figure 2 shows substantially the same arrangement, but with the acid in the "production"-tower being denitrated down to about 80-100% of the original acid only. These figures also show the increase of the strength of the nitrous vitriol in the following towers. In the modification according to Figure 3 only one Gay-Lussac enclosure is associated with one "production" tower and one denitrating tower, and the acid may be circulated on said Gay-Lussac-tower. In the modification of Figure 4 two Gay-Lussac-enclosures are employed; substantially the entire output of the "production" tower may be fed to the denitrating tower from which the amount in excess of the desired output of commercial sulphuric acid is fed to the last Gay-Lussac tower from which it proceeds towards the front end of the plant as operable nitrosyl-sulphuric acid or nitrous vitriol of proper strength. Figure 5 is a modification with internal circulation of the acid on all or on some of the enclosures, the entire acid from the "production"-tower being for instance fed to the last Gay-Lussac, and the internal circulation provides for the contingency that the acid from the denitrating tower should not be sufficient for the operation of absorption or Gay-Lussac enclosures.

The way of the gases is not indicated in the drawings. The gases first enter the denitrating tower; thence they pass into the "production"-tower, and after leaving the "production"-tower they pass into the first, then into the second, and into the third Gay-Lussac enclosure, as the case may be. The rinsing acid passes in the opposite direction. From the first Gay-Lussac enclosure the bulk of the acid flows to the "production" tower, and a small portion may flow onto the denitrating tower. The acid running off from the denitrating tower is withdrawn as commercial sulphuric acid for the market, and the acid running off from the "production"-tower is returned to the last Gay-Lussac enclosure.

In case of a very good operation of the denitrating tower, that is to say, when the denitrating tower should denitrate more than is required for marketable purposes, the excess of the acid produced therein may also be passed to the last Gay-Lussac enclosure together with the acid running off from the production tower, and as indicated in Figures 4 and 5 of the drawing. These figures also illustrate the modification that the total amount of the acid from the "production"-tower is fed to the denitrating tower from which the acid after the withdrawal of the commercial acid is returned to the last Gay-Lussac enclosure, with the eventuality of circular rinsing, as above explained.

While the arrangements shown are par-

ticularly well adapted for furthering the objects of my invention, other arrangements may be found useful for carrying out my process, and other modifications are possible within the meaning and the ambit of the claims hereunto appended.

I claim:

1. In the art of making sulphuric acid by the nitrogen-oxid method the step of oxidizing sulphurous acid gases which comprises passing said gases and nitrous vitriol of at least fifty-five degrees Bé. strength in the vertical direction in contact with each other and through packed reaction spaces, and regulating the flowing resistance through said spaces, so as to correspond to a pressure ranging from approximately one quarter millimeter to six millimeters water-column for each meter of said vertical flow, and keeping the nitrous strength of the vitriol at the bottom of said spaces within a limit of at least a quarter of the nitrous strength at the top of said spaces.

2. In the art of making sulphuric acid by the nitrogen-oxid method the step of oxidizing sulphurous acid gases which comprises passing said gases and strong nitrous vitriol of at least fifty-five degrees Bé. strength through a comparatively large-sized, relatively densely and irregularly packed uninterrupted reaction space, regulating the flowing resistance through said space, so as to correspond to a pressure ranging from approximately one quarter millimeter to six millimeters water column for each meter of said vertical flow, keeping the nitrous strength of the vitriol at the bottom of said space within a limit of at least a quarter of the strength at the top of said spaces, and passing the gases escaping from said space in contact with absorbing sulphuric acid, containing nitrous vitriol.

3. In the art of making sulphuric acid by the nitrogen-oxid method the step of oxidizing sulphurous acid gases which comprises passing said gases and strong nitrous vitriol of not less than approximately fifty-five degrees Beaumé through a comparatively large-sized, densely and irregularly packed uninterrupted reaction space, regulating the flowing resistance through said space, so as to correspond to a pressure ranging from approximately one quarter millimeter to six millimeters water-column for each meter of said vertical flow, keeping the nitrous strength of the vitriol at the bottom of said space within a limit of at least a quarter of the nitrous strength at the top of said space, passing the gases, escaping from said space in contact with absorbing sulphuric acid containing nitrous vitriol and feeding said reaction space with the acid produced by said absorption.

4. In the art of making sulphuric acid by the nitrogen-oxid method the step of oxidiz-

- ingly treating sulphurous-acid gases which comprises passing said gases in contact with strong nitrous vitriol and in the vertical direction through substantially closely packed large uninterrupted reaction spaces presenting a resistance to the flow of the gases and vitriol which is equivalent substantially to a pressure of from one quarter millimeter to about six millimeters for each vertical meter of said packed reaction spaces, keeping the nitrous strength of the vitriol flowing off from said spaces within at least a quarter of the nitrous strength of the vitriol fed to said spaces, absorbing the then escaping gases in sulphuric acid containing nitrous vitriol and re-using the vitriol thus obtained for the feeding of the said reaction spaces and for said absorption.
5. In the art of making sulphuric acid by the nitrogen-oxid method the method comprising the passing of sulphurous acid gases in oxidizing contact with strong nitrous vitriol of substantially 55 degrees Beaumé strength in the vertical direction and in substantially closely packed uninterrupted reaction spaces containing substantially granular packing material, keeping the nitrous strength of the vitriol running off from such spaces within at least a quarter of the nitrous strength of the vitriol fed thereto and the resistance to flow in the packed reaction spaces at at least a quarter of a millimeter pressure for each vertical meter of packed reaction space, absorbing the gases, escaping from said reaction spaces in sulphuric acid containing nitrous vitriol, and re-circulating the nitrous vitriol in the reaction spaces and the nitrous vitriol obtained by absorption in contact with the gases and gaseous reaction products.
6. In the art of making sulphuric acid the method which comprises passing sulphurous acid gases in oxidizing contact with nitrous vitriol in the vertical direction through large closely packed uninterrupted acid production spaces, keeping the nitrous strength of the nitrous vitriol flowing off from said spaces within at least one quarter the nitrous strength of the vitriol fed to said spaces, passing the gases escaping from the production spaces through large absorbing spaces in contact with sulphuric acid containing nitrous vitriol, feeding part of the liquid flowing off from the production spaces to the absorption spaces, and denitrating the balance of the liquid from said production spaces, and feeding nitrous vitriol discharged from the absorption spaces into the production spaces.
7. In the art of making sulphuric acid the method, which comprises passing sulphurous acid gases in oxidizing contact with nitrous vitriol of at least about 55 degrees Beaumé strength through a large, substantially closely packed reaction enclosure, keeping the nitrous strength of the nitrous vitriol flowing off from said enclosure within at least one quarter the nitrous strength of the nitrous vitriol fed thereto, causing the then escaping gases of reaction from said enclosure to enter into the upper part of an additional enclosure in contact with cooled sulphuric acid containing nitrous vitriol thereby absorbing said escaping gases in said sulphuric acid, and feeding the thereby resulting absorption acid to the other enclosure.
8. In the art of making sulphuric acid the method, which comprises passing sulphurous acid gases in oxidizing contact with strong nitrous vitriol of at least fifty-five degrees Bé strength through a substantially closely packed large voluminous uninterrupted reaction enclosure, presenting a resistance to the flow equalizing a pressure of about one quarter millimeter to about six millimeters water column for each vertical meter of reaction enclosure, keeping the nitrous strength of the vitriol flowing off from said enclosure within at least a quarter of the nitrous strength of the vitriol fed thereto, passing the gases escaping from said enclosure in contact with sulphuric acid, thereby absorbing said gases and forming nitrous vitriol and feeding the thus obtained nitrous vitriol to the reaction enclosure.
9. In the art of making sulphuric acid the method, which comprises passing sulphurous acid gases in oxidizing contact with strong nitrous vitriol of at least 55 degrees Beaumé strength and through a substantially closely packed uninterrupted reaction enclosure, preventing full denitration of the nitrous vitriol at the bottom of said enclosure, passing the gases escaping from said enclosure in absorbing contact with sulphuric acid in absorbing enclosures, re-circulating the whole of the nitrous vitriol and the sulphuric acid respectively in said enclosures, feeding the sulphuric acid with the absorbed gases from the last mentioned enclosures to the reaction enclosure, and denitrating vitriol-liquid running off from the reaction enclosure outside of said enclosure.
10. In the art of making sulphuric acid the method which comprises passing sulphurous acid gases in oxidizing contact with strong nitrous vitriol of at least fifty-five degrees Bé strength through a substantially closely packed uninterrupted reaction enclosure, keeping the nitrous strength of the liquid flowing off from said enclosure within at least a quarter of the nitrous strength of the vitriol fed to the enclosure, passing the gases escaping from said reaction enclosure through an absorption enclosure less densely packed than the reaction enclosure and in contact with absorbing sulphuric acid, thereby absorbing said gases and forming nitrous vitriol, feeding the thus obtained nitrous vitriol to the reaction enclosure, and deni-

trating vitriol obtained from the lower part of the reaction enclosure outside of said enclosure.

11. In the art of making sulphuric acid 5 the method which comprises passing sulphurous acid gases in oxidizing contact with strong nitrous vitriol in the vertical direction and in contact with substantially granular packing material in a reaction enclosure, 10 keeping the nitrous strength of the liquid flowing off from said enclosure within at least a quarter of the original nitrous strength of said nitrous vitriol, passing the gases escaping from said reaction enclosure 15 through and in contact with absorbing sulphuric acid and re-circulating the said escaping gases in contact with said absorbing acid, thereby producing nitrous vitriol, feeding said vitriol to the reaction enclosure, and de- 20 nitrating liquid from the lower part of said reaction enclosure outside of said enclosure.

12. In the art of manufacturing sulphuric acid causing sulphurous acid gases of comparatively moderate temperature to react 25 upon nitrous vitriol of at least 55 degrees Bé. strength in tower-like enclosures of at least 210 square feet sectional area each, maintaining a nitrous strength of at least one quarter the original nitrous strength in 30 the acid running off from said enclosures, denitrating the acid produced in some of said enclosures and feeding the acid from the rest of said enclosures and the gases evolved to gas absorbing spaces.

- 35 13. In the art of manufacturing sulphuric acid causing sulphurous acid gases to react at about fifty degrees centigrade upon nitrous vitriol of at least 55 degrees Bé. strength in uninterrupted spaces of at least 210 square 40 feet sectional area each, maintaining a nitrous strength of at least one quarter the original strength in the acid running off from said spaces, denitrating part of said run-off acid, and absorbing the gases resulting 45 thereby and the gases from said uninterrupted spaces in nitrous vitriol.

14. In the art of manufacturing sulphuric acid causing sulphurous acid gases to react at about fifty degrees centigrade upon nitrous 50 vitriol of at least 55 degrees Bé. strength within a packed uninterrupted reaction space of large extent of at least 210 square feet sectional area, denitrating some of the acid produced, allowing the gases evolved in said 55 reaction space and those resulting from the denitration to flow in contact with new quantities of absorbing nitrous vitriol both in a downward direction, and denitrating part of the acid thereby produced together with 60 the acid above mentioned.

15. In the art of manufacturing sulphuric acid causing sulphurous acid gases at moderate temperature of substantially fifty degrees centigrade to react upon nitrous vitriol 65 of at least 55 degrees Bé. strength within a

large packed and uninterrupted reaction space of at least 210 square feet sectional area, maintaining the nitrous strength of the acid discharged from said space, so as to amount to at least one quarter of the original nitrous strength of nitrous vitriol, denitrating part of said run-off nitrous vitriol-containing acid, causing the gas evolved in said reaction space and by denitration to flow in the downward direction together with absorbing nitrous vitriol in a plurality of serially arranged communicating enclosures, and causing the entire amount of nitrous-vitriol-acid present in some of said last mentioned enclosures to re-circulate several times through the respective enclosures.

16. In the art of manufacturing sulphuric acid causing sulphurous acid gases at moderate temperatures of substantially fifty degrees centigrade to react with very large volumes of nitrous vitriol of at least 55 degrees strength within a packed large uninterrupted reaction space of an extent much in excess of the reacting sulphurous acid gases, maintaining the nitrous strength of the acid discharged from said space at not less than one quarter the original nitrous strength of the vitriol, denitrating part of said discharged acid together with additional amounts of nitrous vitriol, acting with the evolved gases upon separate quantities of absorbing nitrous vitriol in a downward direction and circulating said gases in contact with said absorbing vitriol from the last towards the first of said quantities of vitriol in corresponding communicating separate enclosures.
